United States Patent Office

Des. 206,147
Patented Nov. 8, 1966

206,147

KNOB

La Verne E. Clayton, Rockford, Ill., assignor to Amerock Corporation, Rockford, Ill., a corporation of Illinois

Filed Jan. 17, 1966, Ser. No. 653

Term of patent 14 years

(Cl. D10—8)

FIGURE 1 is a front view of a knob incorporating my new design.

FIG. 2 is a side view of the knob.

FIG. 3 is a sectional view taken along the line 3—3 in FIG. 1.

FIG. 4 is a sectional view taken along the line 4—4 in FIG. 1.

I claim:

The ornamental design for a knob, substantially as shown.
